UNITED STATES PATENT OFFICE.

JOHN R. FRANCIS, OF ROCHESTER, NEW YORK.

AUTOMATIC HASP-LOCK.

1,307,966.

Specification of Letters Patent. Patented June 24, 1919.

Application filed January 20, 1919. Serial No. 272,132.

To all whom it may concern:

Be it known that I, JOHN R. FRANCIS, a citizen of the United States of America, residing at Rochester, in the county of Monroe and State of New York, have invented new and useful Improvements in Automatic Hasp-Locks, of which the following is a specification.

This invention relates to improvements 10 in locks, and especially to locks of the hinge or hasp type in which the lock case is mounted on a hasp and may be moved therewith toward and from a stationary member such as a staple.

15 One object of the invention is to provide an improved hasp lock of this type which is adapted to be used on mail sacks, or on heavy straps used for baggage, hampers, etc.

20 Another object of the invention is to effect improvements in the construction of the bolt, and in which the bolt comprises a key operated member and a locking member which is movable with the key operated 25 member to one position, in one direction, and in which each of said members, is independently movable in the opposite direction, and to also provide a spring for independently moving the said members.

30 Another object of the invention is to provide an improved lock of this type embodying a bolt member for moving a locking member to release position, and also embodying a spring detent to normally hold 35 said bolt member in initial position, and a key for use in releasing the detent from the bowed member and for also enabling the bowed member to be manually moved to release position.

40 With the above and other objects in view the invention consists in the construction, combination and arrangement of devices hereinafter described and claimed.

In the accompanying drawings:

45 Figure 1 is a plan of an automatic hasp lock constructed and arranged in accordance with my invention and showing the same in use on a mail sack.

50 Fig. 2 is a longitudinal sectional view of the same on the plane indicated by the line 2-2 of Fig. 1.

55 Fig. 3 is a vertical transverse sectional view of the same on the plane indicated by the line 3-3 of Fig. 1.

55 Fig. 4 is an inverted plan of the lock

case and the lock mechanism, showing the lock case detached from the hasp.

Figs. 5 and 6 are detail views.

My improved lock is here shown as arranged for use on a mail sack. The hasp 66 1 which forms one side of the lock case 2 is hinged as at 3 to a plate or bar 4, which plate or bar is secured as by means of rivets 5 to one side of the neck of a mail sack and is provided with an offset 5 which forms 65 a transverse recess 6 for the reception of the free end of a strap 7, the said strap being adapted to be passed around the neck of the mail sack and being secured at one end thereto as at 8. A stationary locking 70 member 9, which is here shown as a staple is secured to the recessed portion of the plate or bar and is arranged to be passed through a slot 10 near the free end of the strap and to be also passed through a slot 75 11 in the hasp and to enter the lock case, when the hasp is closed. The free end of the strap is here shown as reinforced by a beveled sheet metal strip 11' which is riveted thereto and is arranged on opposite 80 sides thereof.

The lock case is provided in its outer side with a key hole slot 12 and also with a slot 13 which forms an extension of the broadened end of the key hole slot. The 85 bolt comprises a key operated member 14 and a locking member 15, the said members being arranged for longitudinal movement in the lock case and the member 14 having a key hole 16. Said member is also provided on one side with a shoulder 18. Detent springs 19, which are secured at one end, as at 17, to one side of the lock case, are arranged to engage at their free ends 90 on one side of the member 14, and against the shoulder 18 to lock the member 14 in initial position. The slot 13 permits the member 14 to be manually moved by the key against the tension of a spring 24, after the key has been turned a sufficient distance to disengage the detent 19 from the stop shoulder 18. The member 15 in the locking member, is arranged at one end of the member 14 and has a recess 21 in the end which is opposed to the member 14, to 100 receive the staple or stationary member 9, when the hasp is closed, said member 15 also having a lug 22 to engage the staple and thereby lock the hasp in closed position, and hence also lock and firmly secure the strap 110

around the neck of the mail sack. The lug 22 has an inclined cam face 23 to strike the outer end of the staple while the spring 24 serves to snap the member 15 into locking relation to the staple and to hold the member 15 against the end of the member 14.

Normally the member 15 is held in locking position engaged with the staple, by the spring 24. The construction of the bolt, 10 comprising the key operated member 14 and the locking member 15, independently movable in one direction by the spring 24, enables the device to be locked by simply closing the hasp against the bar or plate after the free 15 end of the strap has been engaged with the staple. Such closing of the hasp causes the staple to enter the lock case and strike the cam face of the lug 22 and thus cause the member 15 to move first against the tension 20 of the spring 24 a sufficient distance to clear the outer end of the staple, the said spring then moving the member 15 in the reverse direction, as will be understood, and engaging the lug 22 under the outer end of the 25 staple. When it is desired to unlock the device, the key is inserted in the key hole 12, 16 partly turned a sufficient distance to disengage the detent springs 19 from the shoulder 18 and is then employed to enable the 30 member 14 to be manually moved against the tension of the spring 24, such movement of the member 14 causing said member to push the member 15 against the tension of the spring 24 and to disengage the lug 22 35 from the hasp staple.

The key may be of any suitable construction, and any suitable number of the detent springs 19 may be employed. The lock case may be secured to the staple by any suitable 40 means and the various parts of the lock and the hasp may be made of any suitable material.

While I have herein shown and described the preferred form of my invention, I would have it understood that changes may be made in the form, proportion and construction of the several parts, without departing from the spirit of my invention, and within the scope of the appended claims.

60 I claim:

1. In a lock of the class described, a casing

having a key hole and a slot forming an extension of the key hole; a locking member movable in the casing and comprising a key operated member and a locking member, said locking member being movable by the key operated member in one direction, a spring to independently move the said members in the reverse direction, a spring detent to hold the key operated member in initial position, 55 and a key, engageable with said member to release the detent, and also movable manually in the slot of the casing to move said key operated member against the tension of the spring and thereby cause the locking member to also be moved against the tension of its spring.

2. In a lock of the class described, a casing having a key hole and a slot forming an extension of the key hole; a locking member movable in the lock and comprising a key operated member and a locking member, said locking member having a spring bolt and being movable independently of the key operated member to engage a staple or the 70 like and being movable by the key operated member in one direction, a spring to independently move the said member in the reverse direction, a detent to hold the key operated member in initial locking position, and a key engageable with the last named member to release the detent and also movable manually in the slot of the casing to move said key operated member against the tension of the spring and thereby cause the locking 75 member to be also moved against the tension of its spring into release position.

3. A lock of the class described, a staple, a lock having a casing hingedly mounted for movement toward and from the staple, a 90 spring actuated U-shaped slide, a suitable engaging lug carried by the slide and a spring actuated key operated member movable within the casing and spaced from the staple engaging lug and contacting with the 95 U-shaped slide, whereby the latter may be independently moved through contact of the staple with the staple engaging lug to lock the lock or operated by the movement of the key engaging member to release the staple. 100

In testimony whereof I affix my signature.
JOHN R. FRANCIS.
